UNITED STATES PATENT OFFICE

GEORGE HUNT, OF SOUTH BEND, INDIANA, ASSIGNOR TO THE STUDEBAKER CORPORATION, OF SOUTH BEND, INDIANA, A CORPORATION OF NEW JERSEY

SPRING SHACKLE

Application filed November 21, 1927. Serial No. 234,693.

This invention relates to vehicle springs and more particularly to means for shackling the springs to the vehicle frame.

Heretofore, it has been the practice to provide spring shackles with shackle pins which have movement transversely of the springs. Some of these shackles consisted of a bolt extending through the shackle links and spring eye and a nut threaded on the bolt to draw the links loosely against the sides of the spring eye. It has been found from tests, that when a vehicle turns a corner, or for other reasons the shackle pins move longitudinally in the spring eyes and usually remain in that position. Further tests have revealed that practically all the squeaking noises in spring shackles come from these conditions in which the shackle pins have moved as just described, allowing the shackle links to contact with and rub against the sides of the spring eye and spring hanger. Hence, it is the principal object of the present invention, to provide a spring shackle with means for anchoring the shackle pins against longitudinal movement in order to prevent frictional engagement between the shackle links and the sides of the spring.

Another object is to provide a spring shackle with a two-piece shackle pin which holds the shackle links in spaced relationship relative to the sides of the spring to prevent frictional contact between the same, whereby squeaking noises are avoided.

A further object is to provide a spring shackle with a two-piece non-rotatable shackle pin, each portion thereof having an integral collar abutting against the sides of the spring eye, one portion thereof having a projecting dowel receivable by a recess in the other portion to insure perfect alignment thereof in the spring eye, the ends of the pin portions holding the shackle links in spaced relationship relative to the sides of the spring eye to prevent rubbing engagement between

the same, whereby squeaking noises are avoided.

These being among the objects of the present invention, the same consists of certain features of construction and combinations of parts to be hereinafter described with reference to the accompanying drawing, and then claimed, having the above and other objects in view.

In the accompanying drawing which illustrates a suitable embodiment of the invention,

Figure 1 is a side elevation showing a spring connected to a vehicle frame by a shackle, certain parts being broken away and in section to more clearly show the invention.

Figure 2 is an enlarged partial section taken on the line 2-2 of Figure 1, more clearly showing the shackle construction.

Referring to the accompanying drawing, in which like numerals refer to like parts throughout the several views, the vehicle frame side channel 10 is provided with a conventional depending spring hanger 11 secured thereto in horizontal and vertical planes by rivets 12. The vehicle spring 13 and frame spring hanger 11 are connected by a pair of spaced shackle links 14, one link being positioned at one side of the spring 13 and spring hanger 11, and the other being positioned at the other side of the same.

The lower end of the spring hanger 11 is provided with a circular serrated opening 15 which receives the upper shackle pin. This pin comprises two portions 16 and 17, each of which has a serrated cylindrical surface, a circumferential collar or shoulder 18 adjacent the outer end, and a circumferential curved bearing surface 19 formed by filleting the intersection of the cylindrical surface and outer end faces. These portions 16 and 17 are forced into the serrated opening 15 with a press fit at each side of the hanger 11 and the shoulders 18 of each abut against the adjacent side of the hanger 11. The pin por-

tion 17 is provided with a central integral dowel 20 at its inner end, which is telescopically received in a central opening 21 in the inner end of the pin portion 16 to insure perfect alignment of the two portions 16 and 17.

5 The end of the spring 13 is rolled upwardly and rearwardly to provide a spring eye 22 which receives the lower shackle pin. This pin is identical with the upper pin and will not be described. The shoulders of this two-part pin also abut against the sides of the spring eye 22.

10 The shackle links 14 may be stamped from sheet metal or castings as desired, and are formed with cup-shaped ends 23, the depressions of which receive hardened steel ball races 24. The ball races 24 contain a plurality of ball bearings 25 which, when the shackle is completely assembled, seat on the curved 15 bearing surfaces 19 of the shackle pin portions 16 and 17 to carry the entire load of the vehicle. Lubricant retaining rings comprising felt washers 26 surrounding the ends of the pin portions and enclosed by metallic 20 casings 27, seat within the ball races 24 to prevent the lubricant for the bearing surfaces from escaping from the ball races 24. 25

25 The shackle links 14 are separated by a spacer tube 28 extending therebetween and 30 are secured together by a bolt 29 extending through the spacer tube 28. A nut 30 threaded on the end of the bolt 29, holds the shackle in assembled position. If desired, a plurality of shims 31 may be inserted between the 35 ends of the spacer tube 28 and the links 14 to allow the shackle to be adjusted to obtain the correct bearing pressure between the ball bearings 27 and their respective bearing surfaces.

40 The pin portions 16 and 17 hold the shackle links 14 in spaced relationship relative to the sides of the spring hanger 11 and spring 13 so that there is no possibility of frictional contact between the same. This is a decided 45 advantage over constructions used heretofore, because the squeaking noises which usually occur in spring shackles are avoided.

Formal changes may be made in the suitable embodiment of the invention described 50 without departing from the spirit and substance of the invention, the scope of which is commensurate with the appended claims.

What I claim is:

1. The combination with a vehicle frame 55 and spring, of means connecting said spring to said frame comprising a spring hanger secured to and depending from said frame and having a transverse opening therein, a pair of pins extending into said opening at 60 opposite sides of said hanger, one of said pins having a central cylindrical recess formed in its inner end, an integral central dowel formed on the inner end of the other of said pins, said dowel being telescopically received of 65 by said recess to insure axial alignment of

said pins in said hanger opening, integral circumferential shoulders formed on said pins adjacent the outer ends thereof to abut against the sides of said hanger, and a pair of spaced complementary links pivotally connected at their lower ends to said springs and pivotally supported at their upper ends by said pins, said pins spacing said links from the sides of said spring hanger and preventing transverse movement thereof.

2. The combination with a vehicle frame, of a spring having an end rolled to provide a spring eye, a pair of pins extending into said eye from opposite sides thereof, one of said pins having a central cylindrical recess in its inner end face, a central integral dowel formed on the inner end face of the other of said pins, said dowel being telescopically received by said recess to insure axial alignment of said pins in said spring eye, integral circumferential flanges on said pins adjacent the outer ends thereof abutting against the sides of said spring, and a pair of spaced oppositely disposed links connected at their upper ends to said frame and pivotally connected at their lower ends to the ends of said pins, said pins spacing said links from the sides of said spring to restrain said links from engaging therewith.

3. In a shackle for connecting a vehicle frame and a vehicle spring, a spring hanger secured to said frame having a serrated transverse opening, a serrated spring eye rolled in an end of said spring, a pair of shackle pins having serrated cylindrical surfaces extending into said serrated hanger opening from opposite sides thereof, integral circumferential flanges adjacent the ends of said pins abutting against the sides of said spring hanger, a second pair of shackle pins having serrated cylindrical surfaces extending into said spring eye from opposite sides thereof, integral circumferential flanges adjacent the outer ends of said second pair of pins abutting against the sides of said spring eye, and a pair of oppositely disposed shackle links pivotally connecting the ends of said pair of pins, said serrated surfaces of said pins restraining said pins against rotation in said hanger and spring eye, and said shoulders on said pins restraining said links from engaging the sides of said hanger and spring.

4. A spring shackle comprising a pair of spaced complementary links, and pins pivotally mounted within said links adjacent the ends thereof, each of said pins comprising a female member and a male member joined together intermediate the outer ends thereof, and flanges on said pin members to prevent transverse movement of said joined pin members.

5. A spring shackle comprising a pair of spaced complementary links, means extending between and secured to said links to prevent their separation, and a pin having a

bearing, said pin being composed of a plurality of sections extending between and pivotally mounted in said links, said pin having serrations formed thereon to restrain the same against rotative movement in its bearing, and means on said pin sections to prevent longitudinal movement of said pin in its bearing.

5 Signed by me at South Bend, Indiana, this
10 18th day of November 1927.

GEORGE HUNT.
